UNITED STATES PATENT OFFICE

1,943,984

PHOTO-ELECTRIC TUBE

Theodorus Hendrik Nakken, New York, N. Y., assignor to Nakken Patents Corporation, a corporation of Delaware

Application May 27, 1930. Serial No. 456,062

2 Claims. (Cl. 250—27.5)

In my work in connection with the fabrication of commercial photoelectric tubes, I have found that more is required than the mere provision of an electrically conducting support connected to the cathode lead and the provision of a coating of photoelectric metal on such support. I have found that it is highly expedient to utilize atomic forces and to relate atomic forces deliberately in order to attain a proper process for the fabrication of photoelectric tubes.

In my work I have found, of course, that the most sensitive photoelectric metal, that is, the photoelectric metal most responsive to light, is most desirable for employment provided its tendency to wander may be corrected.

In connection with this thought, caesium is the most sensitive photoelectric metal, rubidium the next, and potassium the next. These in the inverse order are respectively of the sixth, fifth and fourth periodic series but all in the first group.

My selection of a means for checking this tendency to wander is, of course, limited to a material which will provide other necessities in the fabrication of a photoelectric tube, for example, it is a convenience that the inner wall of the bulb serve as the mechanical support. One important limitation, therefore, is the selection of a medium which may be with convenience and dispatch applied to this inner wall and which will cohere or adhere thereto dependably. Another limitation is that it must be conductive and capable easily of forming a conductive connection with the cathode lead-in.

Although it is true that heretofore photoelectric tubes have been fabricated in which the quality of conductiveness for electricity and adhesion to the inner wall have been fulfilled, there has been no regard had to the function of imprisoning the photoelectric metal against its tendency to wander. My experiments, studies and commercial work have led me to the belief that chemical combinations should be avoided in the accomplishment of this end in the prevention of wandering but that utilization of that atomic affinity short of chemical combination which may be called a tendency to amalgamate or alloy lends itself most beautifully to this task. I am of the belief that when utilizing this atomic affinity I in no way impair the photoelectric qualities of the highly sensitive photoelectric metals but merely control their physical state and imprison them against this wandering tendency.

The highest degree of attainment for my objective lies in the association of the most capable

substance which has the base qualities for a supporting conducting coat relatively to its imprisoning function against this tendency to wander, and I am of the belief that this spells the selection of material which has the nearest identical interatomic structure to the photoelectric metal to be imprisoned, for example, barium, which has the required qualities of conductivity, capability of being vaporized at workable temperatures, capability of being condensed upon the cool inner surface of a glass bulb, capability of maintaining itself in close cohesion with the inner surface of the glass bulb, capability of resisting all variations of normal working temperatures, has in addition the quality of extreme closeness as to interatomic structure to caesium, the most capable photoelectric metal. It, therefore, is highly desirable as the first inner coat for the photoelectric tube to receive and hold against wandering a film of photoelectric caesium.

To a lesser degree, strontium possesses this similarity of interatomic structure and is serviceable to imprison caesium against wandering but should perhaps be the most desirable substance for imprisoning rubidium. In the same way, calcium is related to potassium and magnesium to sodium. But I have found that magnesium serves well as an imprisoning coating not only for potassium but for rubidium and caesium. I have found, in addition, that rubidium has a great alloying or imprisoning tendency with respect to caesium and that potassium has this imprisoning tendency for caesium and for rubidium, while magnesium most closely tends to amalgamate with potassium of the three elements potassium, rubidium and caesium.

I, therefore, have conceived and found it to be true that a series or stages of imprisoning layers may be employed, for example, a base coating of magnesium may have a film of potassium, the potassium may have a superposed film of rubidium and the rubidium may have a superposed coating of caesium, whereby the imprisoning of the tendency to wander is more effective than if magnesium be used directly against a coating of caesium. In fact, this graded series is as effective in preventing wandering and leaving a photoelectric metal free to function photoelectrically as would be a correlation between a base coating of barium to imprison a film of caesium. The thought which I am bringing out is in substance that the closer to identity with respect to interatomic structure between two contiguous films of these metals, the closer is

the affinity therebetween without the production of a chemical compound.

In practicing my invention, my experiments and deductions have led me to the belief that 5 the various coatings for my photoelectric tube should be limited to the metals of the first two periodic groups and that it is probably preferable to associate only two coatings both in the same numbered periodic series such as barium with 10 caesium and strontium with rubidium, although I contemplate the staging of the coatings as, for example, the employment of magnesium next the glass and a next inner coating of potassium, a second inner coating of rubidium and a third 15 inner coating of caesium, by which arrangement in series each coating with relation to the next adjacent coating either outer or inner is quite close with relation to its interatomic structure.

Of course, the general object of my invention 20 is to improve in general both the method of manufacturing highly efficient photoelectric tubes and to produce photoelectric tubes of the best performance as to durability, dependability and cheapness of manufacture.

25 The above and further objects of the invention are pointed out more particularly in the following claims which are directed to illustrative embodiments of my invention described in the 30 diagram of the accompanying drawing wherein Fig. 1 is a sectional view and Fig. 2 is a modification thereof. All the descriptions, of course, are solely by way of illustration and not limitation.

35 In the drawing, a commercial glass bulb A having any usual connection 1 to the exhaust system is employed. This bulb is provided with a cathode lead-in 2 and an anode lead-in 3, the cathode lead-in 2 preferably having a portion 40 4 lying physically in close contact with the exposed inner surface of the bulb A. The lead-in 3 is shown serving as a support for the anode 5. The anode lead-in 3 is preferably shielded from 45 a conductive metal deposit as by a glass tubular extension 6 and by the platform 7, which platform may be supported by glass embedded supports 8 and 9.

Connected with one end of the bulb A by means 50 of the throat 10 is another glass chamber 11 carrying a heat resisting metal capsule 12 preferably of molybdenum in which is a charge 13 of the desired photoelectric metal or of the chemical compound capable upon heating of liberating the desired photoelectric metal. It is to 55 be understood that the capsule 12 may be multiplied and positioned differently within the chamber 11 or that a number of chambers 11, each containing its capsule, may be provided.

In practicing my process, it is preferred that 60 the pill 20 or charge of metal or substance performing the coating next to the glass of the bulb A be located on the heat resisting platform 7 preferably of nickel, silver or molybdenum. I have therefore shown in my diagram a physical separation 65 between the heat resisting metal which sustains the charge of metal to be used as a coating for one coat with respect to another coat and it is, of course, to be understood that this may be multiplied to the extent that deposited or 70 flash coats are to be employed.

In practicing my invention, after the interior of the bulb A has been properly evacuated and after occluded gases have been removed in any approved fashion. I subject the platform 7 to 75 a local positioning of a high frequency coil to

effect a sufficient heating to vaporize the pill 20 which effects its deposit upon the inner walls of the bulb A. This pill 20 may be magnesium or barium. The magnesium or barium deposit forms a coating in electrical connection with the 80 lead-in part 4 and completely covers the interior of the plug except that by the shielding it fails to contact with the anode lead-in 3. I then preferably burn out the window B and burn out the 85 interior of the neck 10.

The substance of the material 20, instead of magnesium, may be any one of the metals of the second periodic group capable of existing in the pure state or in the form of a salt capable of producing the vaporized metal when subjected to 90 heat. If it is desired to employ such a metal as exists only in the form of a salt or in some chemical form requiring physical retaining during the process of heating preliminary to vaporizing, a cartridge like the cartridge 12 may be provided on the platform 7.

The next preferred step is to effect the local heating of the capsule 12 to effect the vaporizing of the metal or substance forming the metal for the next inner coating within the bulb A. With 100 the first coating barium, the charge 13 may well be caesium. The vaporized caesium is discharged through the throat 10 and condenses upon the magnesium or barium inner surface coating of the bulb A. Further exhaustion of the 105 bulb may be continued if desired and it is, of course, to be understood that the occluded gases within the chamber 11 and the capsule 12 have been driven off before flashing the charge within 110 the capsule.

After all the flashings have been accomplished by means of all the chambers 11 that are provided, or by means of all the capsules in a single chamber 11, the bulb A may be sealed off both at the neck 10 and at the pump tube 1 when it is finished 115 ready for employment.

In some cases it may be preferred that the charge 13 be a mixture of photoelectric metals such as potassium, rubidium and caesium, or a mixture of the salts of such metals or any two of them 120 which upon heating are capable of producing a vaporized metal. In this procedure, the inner coatings are deposited in admixture and not as superimposed coatings, but the interrelation as to imprisoning effect is present, nevertheless. 125 Described differently, the caesium on a magnesium base is better held against wandering or creeping when mixed with potassium and rubidium and it appears that it does not require that the potassium with rubidium be deposited in films one 130 under the other.

What I claim and desire to secure by United States Letters Patent is:

1. A photoelectric tube comprising a glass bulb having a cathode lead-in in physical contact with 135 the exposed inner surface of said bulb and an anode lead-in; an inner coating for said bulb of an electrically conducting metal of the second periodic group in electrical connection with said cathode lead-in; an inner exposed coating for 140 said bulb of a sensitive photoelectric metal of the first periodic group; and an intermediate coating layer of one of the metals of the first two periodic groups which more nearly coincides with the interatomic structure of both the two afore- 145 mentioned coatings than does the interatomic structure of said inner coating approach identity with the interatomic structure of said first aforementioned coating.

2. A photosensitive device comprising a vac- 150

uum-tight container; an anode therein; an anode lead-in extending conductively from without said container into connection with said anode; a cathode within said container; a cathode lead-in extending from without said container conductively into connection with said cathode, said cathode comprising on its surface fronting said anode a

plurality of layers of photo-electric elements, each under-layer of which layers differs from the next superimposed layer by one displacement as to its group number and series number in the periodic system of elements.
